(57) CLAIM

The ornamental design for a head for a golf club, as shown and described.

DESCRIPTION

FIG. 1 is a perspective view of a head for a golf club showing my new design;

FIG. 2 is a front view thereof;

FIG. 3 is a left side view thereof;

FIG. 4 is a right side view thereof;

FIG. 5 is a top view thereof;

FIG. 6 is an elevational view taken along line 6-6 end in FIG. 2 thereof;

FIG. 7 is an elevational view taken along line 7-7 end in FIG. 2 thereof; and,

FIG. 8 is an elevational view taken along line 8-8 end in FIG. 2 thereof.

The part of the drawings shown in FIGS. 1-5 in broken lines illustrates a portion of the head for a golf club that forms no part of the claimed design. The part of the drawings shown in FIGS. 6-8 in broken lines and the cross-section portions illustrate portions of the head for a golf club that form no part of the claimed design.
